UNITED STATES PATENT OFFICE.

GEORGE ALBERT THORNHILL, OF ROYAL OAK, LONDON, ENGLAND, ASSIGNOR TO THE MACHINE LABELLING COMPANY, LIMITED, OF LONDON, ENGLAND.

BOTTLE-LABELING MACHINE.

No. 922,974.

Specification of Letters Patent.

Patented May 25, 1909.

Application filed September 8, 1908. Serial No. 452,144.

To all whom it may concern:

Be it known that I, GEORGE ALBERT THORNHILL, a subject of the King of Great Britain, residing at 146 Blomfield Terrace, Royal Oak, in the county of London, England, engineer, have invented certain new and useful Improvements Relating to Bottle-Labeling Machines, of which the following is a specification.

10 The object of this invention is to produce bottle labeling machines constructed so that the downward movements of the bottle-rest will rotate the gumming device and wherein the gumming device is formed of two similar parts mounted to rotate in oppositely disposed troughs, from which the gumming plates collect the gum and travel to a position directly over the label before being lowered on to said label.

15 20 The invention is illustrated in the accompanying drawings, wherein—

Figure 1 is an end elevation showing the position of the parts before the bottle is depressed on to the label; and Fig. 2 is a similar view with the bottle depressed. Fig. 3 is a plan of Fig. 1; and Figs. 4 and 5 are part end elevations of a modification showing the left and right side troughs in the depressed and raised positions respectively.

25 30 The same letters of reference where they occur are used to denote the same or corresponding parts in all the figures of the drawings.

In these drawings *a* is a base or pedestal and *b* is a vertical column having a cylindrically bored core *b'* in which is a spiral or other spring *c*. Telescoping within the core *b'* and resting on the spring *c* is a plunger *d* to the upper end of which is affixed a horizontal plate *d'* carrying the bottle rests *d''*. Extending transversely across the plate *d'* and between the bottle rests *d''* is a leather or other flexible strip *e*, which forms the bed for the labels *f*, the ends of said strip *e* being secured to crank arms *e'* pivoted at *e''* to the upper end of the column *b*. To opposite sides of the column *b* two brackets *g* are affixed or formed integrally, carrying or formed with troughs *h* for the gum or other adhesive.

40 45 50 Referring now to Figs. 1 to 3. Within each trough *h* is rotatably mounted a section of a cylinder *j* having one flat longitudinal face *j'* and hinged or otherwise pivotally mounted thereto is a gum carrier, in the form of a flat plate *k*, of sufficient size to gum half

of the label, and adapted to rest on the flat face *j'* of the cylinder section *j* when in the depressed position shown in Fig. 2. This plate *k* is provided with a forwardly projecting fixed arm *k'* which serves to carry the gumming plate *k* over the label bed *e* until the said plate *k* is in the extreme forward position, whereupon it falls, by gravity, on to the contiguous half face of the label *f*. This is the position shown in Figs. 1 and 3. 60 65 Each cylinder section *j* is rotated by means of an arm *l* fixed to the bottle carrier plate *d'* and provided with a toothed rack *l'* which gears with a pinion *j''* on the spindle *j''* of the cylinder section. Each gumming plate *k* 70 collects the gum from the flat face *j'* of its cylinder section *j* and carries the same to the label, and each plate is adapted to supply the gum to one-half of the label and the plates *k* advance and retire to and from their respective cylinder sections by the downward and upward movements of the bottle carrier, leaving the gummed label exposed to the pressure of the bottle when the carrier is in the depressed position shown in Fig. 2. By 75 80 85 this arrangement the gum is supplied to the whole surface of the label, and owing to each half of the gumming device being caused to move in opposite directions there is no tendency for the label to be pushed or drawn away from its proper position.

In the modification shown in Figs. 4 and 5 each rotatable cylinder section *j''* is mounted in the trough *h* so that its curved face *j''* will supply the gum to a roller *m* rotatably 90 mounted in pivoted brackets *m'* in the trough *h*, from which roller *m* the gumming plate *k* collects the gum and carries it to the label. Each rotatable cylinder section *j''* is also provided with a fixed arm *j''* which projects beyond the side of the trough *h* and terminates in a cam-shaped head *j''* against which bears a lever arm *l''* pivoted at *l'''* to the vertical column *b* and connected by a link *l''* to the bottle carrier plate *d'*. By this arrangement the sections *j''* are rotated from the position shown in Fig. 5 to that shown in Fig. 4 by the depression of the bottle carrier plate *d'*, returning to the initial position by gravity 95 100 105 acting on the counterweighted parts *j''* of the sections.

The mode of operation is as follows:—A suitable number of labels *f* is placed upon the label bed *e* and a bottle *n* placed on the bottle rests *d''* is first pressed downward, causing 110

the sections j or j' to rotate in the troughs h and collect the gum therefrom. The upward movement of the bottle carrier causes the gumming plates k to advance across the 5 label bed e and gum the label, downward pressure of the bottle will then cause the gumming plates to return to their rotatable sections j or j' and at the same time the label will be caused to adhere to the bottle by the 10 pressure on the label bed e , which latter is constructed of flexible material as stated so as to conform, on depression, to the round shape of the bottle. The upward movement of the bottle carrier will again rotate the sections j or j' and cause the gumming plates k to advance over and gum the next succeeding label ready for the next bottle, and so on with each succeeding bottle.

Having fully described my invention, what 20 I claim and desire to secure by Letters Patent is:—

1. A bottle labeling machine comprising a vertically movable bottle carrier, a relatively stationary label bed, a two-part gumming 25 device in which the parts move in opposite directions across the stationary label bed, and a connection between each part of the gumming device and the bottle carrier, so that the parts of the gumming device will be 30 rotated by the depression of the said carrier, substantially as described and for the purposes stated.

2. A bottle-labeling machine, comprising a vertically-movable bottle-carrier, a relatively stationary label bed, a two-part gumming device in which the parts rotate in opposite directions, a gumming plate pivoted to each part of the gumming device, each of 35 said gumming plates having a forwardly-projecting arm and being so connected to the rotating gumming device as to be caused to travel to the center of the label-bed before the gumming plate is lowered thereon, and a connection between each part of the gumming device and the bottle-carrier, so that the parts of the gumming device will be rotated by the depression of the said carrier, substantially as described and for the purposes stated.

50 3. A bottle labeling machine comprising a

vertically movable bottle carrier, a relatively stationary label bed, a two-part gumming device in which the parts are mounted to rotate in oppositely disposed troughs, from which the gum is taken, each part having a 55 gumming plate pivoted thereto, and a connection between each part of the gumming device and the bottle carrier, so that the parts of the gumming device will be rotated by the depression of the said carrier, substantially as described and for the purposes stated.

4. A bottle labeling machine comprising a vertically movable bottle carrier, a relatively stationary label bed, a gumming device 60 formed of two similar parts mounted to rotate in oppositely disposed troughs and each in working relation with a pivoted gumming plate provided with a forwardly projecting arm, such gumming plates moving in oppositely disposed directions across the stationary label bed, and a connection between each part of the gumming device and the bottle carrier, so that the parts of the gumming device will be rotated by the depression of the 65 said carrier, substantially as described and for the purposes stated.

5. A bottle labeling machine comprising a vertically movable bottle carrier, a relatively stationary label bed secured to crank arms 70 pivoted to a fixed part of the machine, two gum troughs disposed on opposite sides of the label bed, a gumming device rotatably mounted in each of said troughs, a gumming plate pivoted to such gumming device and having a forwardly projecting arm, and a connection between each part of the gumming device and the bottle carrier, so that the parts of the gumming device will be rotated by the depression of the 75 said carrier, substantially as described and for the purposes stated.

In testimony whereof I have hereunto set my hand in presence of two subscribing witnesses.

GEORGE ALBERT THORNHILL.
